UNITED STATES PATENT OFFICE

146,341

DESIGN FOR A WASHING MACHINE

George W. Walker, Detroit, Mich., assignor, by
mesne assignments, to Hyman D. Brotman,
Detroit, Mich.

Application March 15, 1945, Serial No. 118,505

Term of patent 14 years

(Cl. D49—1)

To all whom it may concern:

Be it known that I, George W. Walker, a citizen of the United States, residing at Detroit, in the county of Wayne and State of Michigan, have invented a new, original, and ornamental Design for a Washing Machine, of which the following is a specification, reference being had to the accompanying drawing, forming part thereof.

Fig. 1 is a perspective view showing the front, top and one side of a washing machine showing my new design;

Fig. 2 is a perspective view showing the back and top thereof; and

Fig. 3 is a perspective view showing the front, top and opposite side thereof.

I claim:

The ornamental design for a washing machine, as shown.

GEORGE W. WALKER.
